UNITED STATES PATENT OFFICE.

EDWARD CHESHIRE, OF MILWAUKEE, WISCONSIN, ASSIGNOR, BY MESNE ASSIGNMENTS, TO MIEHLE PRINTING PRESS & MANUFACTURING COMPANY, OF CHICAGO, ILLINOIS, A CORPORATION OF ILLINOIS.

PRINTING PRESS.

Application filed October 11, 1919. Serial No. 329,976.

To all whom it may concern:

Be it known that I, EDWARD CHESHIRE, a citizen of the United States, residing at Milwaukee, in the county of Milwaukee and 5 State of Wisconsin, have invented certain new and useful Improvements in Printing Presses, of which the following is a specification.

This invention relates to printing presses, 10 and more particularly to a cylinder printing press.

One of the objects of this invention is to simplify the cylinder type of printing press, all of the principal motions being rotary 15 or reciprocating, or a combination of the two, and the parts disposed in a manner whereby the same run in perfect balance at comparatively high speed.

Another object is to provide improved 20 cylinder mechanism and associated cooperating parts.

Another object is to make the various parts more accessible.

Another object is to transfer the stock 25 from one part of the press to another in a novel and practical manner.

Another object is to control automatically 30 in an improved manner, the operation of the various parts of the press, and to arrange the parts to cooperate in a given sequence to meet the various requirements for successful commercial operation.

These and other objects are accomplished 35 by the printing press illustrated on the accompanying sheets of drawings, in which—

Figure 1 is a side elevation of my improved printing press, the suction shoe being 40 in position to grip a piece of paper or other stock from the stock pile, and the delivery grippers having just delivered a printed sheet to the jogger.

Figure 2 is an enlarged fragmentary side 45 elevation of the same printing press, the cylinder being in a raised position, in which position the printed sheet is taken therefrom, and in which position another sheet is placed upon the transfer table by the suction feed gripper.

Figure 3 is a vertical sectional view taken 50 just inside of the side frame and from the side opposite to that shown in Figure 2, the

section being taken along the line 3—3 of Figure 5.

Figure 4 is a view taken on the line 4—4 55 of Figure 5.

Figure 5 is a front elevation of the printing press with the stock table removed, the supporting arm of the stock table being 60 shown in section.

Figure 6 is a top plan view of the printing press.

Figure 7 is an enlarged fragmentary side elevation of the cylinder and some of the associated mechanism, the cylinder being in 65 its upper position.

Figure 8 is a transverse sectional view taken through the cylinder along line 8—8 of Figure 9.

Figure 9 is a longitudinal sectional view 70 taken through the cylinder showing some of the cylinder mechanism.

Figure 10 is a plan view of the cylinder showing the grippers.

Figure 11 is a transverse vertical sectional 75 view of the cylinder showing the lock and gripper mechanism, and taken in the plane of line 11—11 of Figure 10.

Figure 12 is a fragmentary side elevation of the cylinder showing the lock for the 80 cylinder gripper.

Figure 13 is a sectional view taken in the planes of the irregular line 13—13 of Figure 12.

Figure 14 is a detail sectional view of a 85 valve forming a part of the pneumatic control mechanism of the printing press.

Figures 15 and 16 are side elevations of 90 cams for controlling the movements of the valve shown in Figure 14, the shaft being shown in section.

Figure 17 is a detail sectional view showing the cam shown in Figures 15 and 16 in plan with their associated mechanism.

Figure 18 is a full-size transverse sec- 95 tional view of the gripper feed mechanism, the suction shoe being shown in side elevation.

Figure 19 is a fragmentary side elevation of the printing press showing primarily the 100 cylinder locking mechanism and the transfer table registry mechanism.

Figure 20 is a fragmentary front elevation of the arrangement shown in Figure 19.

Figure 21 is a detail sectional view taken in the plane of line 21—21 of Figure 20.

Figure 22 is a detail front elevation of a portion of the transfer table side registry mechanism.

Figure 23 is a sectional view taken through the cylinder showing the cylinder lock mechanism and parts for controlling same.

Figure 24 is a sectional view of one of the 10 arms which assist in carrying the suction shoe and showing the pneumatic connection leading through said arm to said shoe.

Figure 25 is a detail plan view of the control valve which is shown in section in 15 Figure 14.

Figure 26 is a plan view of the transfer table.

Figure 27 is a sectional view of the transfer table taken in the plane of line 27—27 of 20 Figure 26, the transfer table being shown in its forwardmost position with respect to the printing cylinder.

The various novel features of my invention will be apparent from the following 25 description and the drawings, and will be particularly pointed out in the appended claims.

This invention is an improvement on the 30 printing press disclosed in my co-pending application Serial No. 224,426, filed March 25th, 1918.

Referring to the figures of the drawings, it will be noted that the main frame of the machine includes two side frames 10 and 11, 35 which are connected to each other by three girts 12, 13, and 14, respectively (see Figures 3 and 4), the girt 12 being the delivery table girt, the girt 13 being the bottom girt at the rear of the machine to which a bracket 40 15 is secured for supporting the motor 16 for driving the operating parts of the press, and girt 14 at the lower front part of the printing press being a bearing girt enclosing gear mechanism for raising and lowering 45 the cylinder, to be referred to hereinafter. Formed integrally with the side frame member 11 is a forwardly extending arm 17 (see Figures 1, 2, 5, and 6) to which is pivotally connected at 18 the stock table 50 mechanism 19, the table proper of which may be raised either automatically or manually by any suitable mechanism for maintaining the stock on the table at a predetermined height, whereby the top sheet may be 55 gripped by the suction feed gripper to be referred to hereinafter. Integrally formed with the delivery table girt 12 is an arm 20 (see Figure 3) which carries the jogger table 21 and the associated jogger mechanism.

60 Mounted upon one end of a shaft 22 of motor 16 (see Figure 6) is a pulley 23 which is maintained thereon by an eccentrically mounted gravity controlled lock washer 24 (see Figure 3). A belt 25 (see Figure 6) 65 passes around pulley 23 and also around a

pulley 26 mounted upon a pinion shaft 26' (see Figure 3) carrying a gear 26^a meshing with and driving a gear 27^a mounted upon the main shaft 27 of the printing press. Operatively associated with shaft 26' is a hand 70 wheel 26^b, whereby the press may be operated by hand.

Cylinder mechanism.

Keyed to the main shaft 27 is a gear 28 75 (see Figure 3) which meshes with and drives a gear 29 mounted upon a hollow double crank shaft 30. Formed integrally with this shaft 30 are two alined crank arms 31 and 32 (see Figures 3 and 4) to the outer ends 80 of which are pivotally connected cylinder connecting rods 33 and 34, respectively, which in turn at their upper ends are pivotally connected at 35 and 36 to cylinder bearings 37 and 38, respectively, (see Figure 25 9). These cylinder bearings are secured to and carried by the cylinder frame 37^a having lateral projecting webs 39 and 40, respectively, which are slidably mounted within guideways 41 and 42, respectively, formed in 90 the side frames 10 and 11, respectively. This cylinder frame is retained in said guideways by gib plates 43 and 44, respectively, which are secured to the side frames 10 and 11.

The cylinder 45 is carried by the cylinder 95 bearings 37 and 38, the latter being held properly spaced by the cylinder proper. This cylinder 45 has two hubs 46 and 47 which are received by the bearings 37 and 38, respectively. These hubs 46 and 47 are 100 formed integrally with the main portion of the cylinder, which includes the semi-cylindrical tympan shell 48 (see Figure 11), upon which the tympan 49 is laid and secured at one end between a portion of the 105 cylinder shell and the cylinder gripper bar 50, which is locked in holding position and released therefrom by two holding arms 51 (see Figures 11, 12, and 13), each of which is mounted eccentrically upon a stud 52, 110 which passes through the cylinder end heads, the eccentric 53 in each case being pinned to a reduced portion of the stud 52, it being understood that the holding arms 51 receive their movement by manually turning the 115 stud 52 by means of a screw driver. The tympan is stretched over the tympan bed 48 and partially secured in position by two square rods or reels 54 and 55 (see Figure 11), which are held in adjusted position by 120 ratchet mechanisms 56' (see Figure 9) at the ends thereof. Slidably mounted in the gripper bar 50 along the length thereof are a plurality of spring pressed cylinder grippers 56 (see Figures 10, 11, and 13), the 125 plungers of which extend radially through the gripper bar, the ends of the plungers each being engaged by a corresponding grip lever 57 (see Figure 11) secured to a grip shaft 58 pivotally mounted between the end 130

heads of the cylinder. Upon one end of the grip shaft is secured a rocker arm 59 carrying at its free end a roller 60 (see Figure 8), which during one part of the revolution 5 of the cylinder passes into engagement with a cylinder gripper trip lever 61 fixed to a shaft 62. Mounted in this lever 61 is a roller 63 lying in the path of movement of two cams, a lower cam 65 and an upper cam 66 10 formed on a slide cam bar 64, which is given a quick reciprocatory movement, at the upper and lower limits of travel of the cylinder 45, by a cam 67 (see Figure 3), the movement from the cam 67 to the slide cam bar 64 15 being transmitted through a cylinder grip lever pivoted intermediate its ends at 68. One arm of the lever carries a roller 69, which traverses the cam 67, and the other arm 70 of the lever is pivotally connected to the 20 lower end of the cam slide bar 64. In other words, it will be seen that the cylinder grippers 56 are opened by mechanism actuated by the cam 67 keyed to the main shaft 27. It will be appreciated that the grippers must 25 be opened rapidly both at the upper and lower limits of the cylinder travel. At the upper end of the cylinder travel the grippers are opened rapidly by cam 66 to permit the delivery grippers 71 to remove the printed 30 stock away from the cylinder, whereupon it is delivered to the jogger table 21. At the lower end of the cylinder travel the cylinder grippers are opened rapidly by the cam 65 for the purpose of permitting the 35 sheet of paper to be properly aligned on the cylinder just preparatory to the time that the cylinder grippers grip the sheet, and preparatory to upward printing movement of the cylinder. The grippers are closed 40 and releasably held closed, as a result of the springs 72 surrounding the gripper plungers (see Figure 11).

Cylinder click mechanism.

45 In this type of machine it is necessary that the cylinder be free to rotate when unlocked for making ready. Normally during the downward movement of the cylinder the latter is unlocked from its driving mechanism but locked against accidental rotation by click mechanism, including a pawl 166 (see Figure 8) carrying a roller 167 which, during the downward movement of the cylinder lies in a notch 168 formed in the rim 50 of the cylinder at one end thereof. This pawl 166 is pivotally connected at one of its ends to a relatively stationary abutment 169 which is mounted upon the cylinder hub 46 and held against rotation by a bolt 170 which secures it to the cylinder bearing. Interposed between an ear on the member 169 and the free end of the pawl 166 55 is a spring 171 which yieldably holds the roller 167 within the notch 168 to prevent accidental rotation of the cylinder. As 60 stated hereinabove, however, it is desirous to rotate the cylinder during make-ready. To accomplish this it is merely necessary to insert in one of a plurality of apertures 172 (see Figure 10) in the periphery of the 65 cylinder rim a suitable rod whereby the cylinder may be given a snap movement, whereupon the roller 167 will be forced out of the notch 168 against the tension of spring 171. It will be understood that the 70 roller 167 will occupy the notch 168 during the downward movement of the cylinder, that is, when the cylinder is not in operation. However, when the cylinder takes its upward rectilinear movement, the latter also 75 rotates and accordingly the roller 167 during such printing operation will not be in the notch 168. However, the roller 167 is presented to the notch 168 at the upper limit of movement of the cylinder at which time 80 the roller 167 clicks into the notch 168 preparatory to the downward movement of the cylinder. 85

Cylinder lock.

90

Under normal operating conditions, the cylinder is rotated through a complete revolution as it is being raised, this movement of the cylinder being the printing movement. At the upper limit of movement, the cylinder is tripped, and accordingly as it is lowered does not rotate, it being understood 95 that the cylinder gap faces the type during the lowering movement of the cylinder. The cylinder also may move upwardly without rotating, in which event the cylinder is unlocked from the driving gearing, this being the case when no material has been fed onto the transfer table, which latter is provided with suction means forming a part of the control system to be referred to later. 100

Referring particularly to Figures 9, 11, and 23, it will be noted that one end wall of the cylinder has secured thereto a fulcrum 73, to which is pivotally connected a lever 74, to one end of which is pivotally connected a movable lock member 75, which may be reciprocated through an opening 76 in one end of the cylinder, said movable lock member being movable into and out of engagement with a cooperating lock member 77 secured to the web 78 of the cylinder driving gear 79, which meshes with a rack bar 80 rigidly secured to and movable up and down with the bed plate 81, it being understood that as the cylinder moves rectilinearly in one direction the rack bar with the cylinder bed moves rectilinearly in the opposite direction. When the lock members 75 and 77 are in locking engagement, the cylinder is caused to rotate, it being understood that during the operation of the machine the cylinder drive gear 79 is continuously in motion during upward and downward movements of the cylinder. If the 115

lock members 75 and 77 are not in locking association with respect to each other, it will be understood that the cylinder is not rotated, even though it is moved vertically up and down. At the same time, however, the gear 79 will be in motion during an upward and downward movement of the cylinder proper. The lock member 75 is yieldably and releasably held in locked and unlocked positions by a spring-pressed plunger 74^a, the end of which is oppositely tapered for engaging a roller 74^b carried at one end of lever 74.

Pivottally connected to one end of the lever 74 is a rod 82 which is coincident with the longitudinal axis of the cylinder. Loosely mounted upon the outer end of the rod 82 (see Figure 23) intermediate a collar 83 and a washer 84 is a saddle block 85, to which is pivottally connected one set of arms 86 of a bifurcated bell crank pivottally supported at 87 on a bracket 88 mounted upon the cylinder bearing 38, the other set of arms 89 of the bifurcated bell crank having pivottally connected at its outer end a dog 90 having a spring 91 which frictionally engages the side walls of the arms 89 to frictionally hold the dog in various positions. This dog 91 lies in the path of movement of two blocks 92 and 93 on a reciprocating bar 94 having at its lower end a roller 95 (see Figure 2) traversing a cam race 96 on a cam mounted upon a reduced portion of shaft 30, and having two cusps 97 and 98 whereby the bar 94 is reciprocated downwardly and upwardly a slight amount with considerably rapidity when the cylinder is at its upper and lower limits of movement, respectively. A pivotal guide member 99 is mounted on the side frame 11 and is connected to the lower end of the bar 94, the upper end of the bar being slidably and guidably mounted in a guide block 100 (see Figure 23) secured to the frame arm 17. The dog 90, which receives motion from the cam bar blocks 92 and 93, transmits motion to the cylinder lock member 75 for locking and unlocking the cylinder with respect to its driving gear 79. The dog 90, and therefore the cylinder lock, is partially pneumatically controlled, as will be described later. In fact, the main control of the machine is pneumatic.

55 *Pneumatic control system.*

A vacuum pump 101, (see Figure 2), driven by the motor 16, is provided for producing a vacuum through a system including a conduit 102 connected to a main control valve 103, the movable portion of which may be operated by conveniently arranged hand levers 104. Connected to this valve 103 is a pipe 105, which in turn is connected to a valve casing 106 and pneumatically connected to a valve chamber 107 (see Figure

14). Slidably mounted in the valve casing 106 are two valves 108 and 109, the former controlling the vacuum extended through a pipe 110 (see Figure 2) telescopically mounted in a vacuum chamber 111 connected 70 to valve vacuum chamber 107, said pipe 110 being connected to a connection 112 (see Figures 19 and 20), in turn connected to a pipe 113 connected to a nipple 114 (see Figure 21) mounted on the transfer table frame 115 75 connected to the other leg of a U-shaped vacuum chamber 119, the passageway 118 being connected to the other leg of the U-shaped 80 chamber, the passageway 117 being connected at the bend of said U-shaped vacuum chamber 119 for purposes to be described later. Secured to the transfer table frame 115 is the transfer table proper 120 (see Figures 26 and 27) provided with a plurality of apertures 121, to which suction is extended, the air being exhausted through pipe 116 toward the vacuum pump. The operation of the machine is controlled through 85 the transfer table, that is to say, when the suction openings 121 are covered by a sheet of material fed from the stock table, the cylinder mechanism is actuated. The cylinder proper, at its upper limit of movement, is unlocked in a manner to be more fully set forth hereinafter, so that the cylinder will not rotate as it moves downwardly. At the same time the piston plunger of a dash pot 122 (see Figure 7) mounted upon 90 the cylinder frame at the left-hand side is forced outwardly by vacuum extended through passageway 117 (see Figure 26) so that it may engage a yieldably mounted motor switch handle to automatically open 100 the motor switch to stop the operation of the machine if the cylinder moves upwardly from its lowest position, with the sheet of material still remaining on the transfer table instead of being taken by the cylinder. Also at the same time when the cylinder and transfer table are at their upper limit of movement, the stem 123 (see Figure 23) of a similar vacuum plunger 124 is caused to move outwardly into engagement with the 110 dog 90, causing the lower end thereof to move into the path of movement of the block 93 mounted on the cam bar 94 so that said block 93 at the lower limit of movement of the cylinder may be given a relatively short 115 and quick upward movement as a result of the cam cusp 98 (see Figure 2) to engage and slightly lift dog 90 (see Figure 23), thereby causing the cylinder lock member 75 to move into engagement with the lock 125 member 77, locking the cylinder for rotation preparatory to its upward or printing movement. When the cylinder reaches its upper limit of movement, the block 92 on cam bar 94 moves slightly downwardly with 130

a quick action as a result of cam cusp 97 and passes into engagement with the upper end of dog 90, throwing lock member 75 out of engagement with lock member 77, or, 6 in other words, unlocking the cylinder and also causing the lower end of the dog 90 to move inwardly out of the path of movement of the block 93 and forcing the vacuum plunger 124 into its inner limit of movement. 10 This unlocking of the cylinder at its upper limit of movement takes place regardless of sheet feeding conditions, but thereafter, as soon as a sheet covers the openings on the transfer table, plunger stem 123 again 15 is moved outwardly to perform its function. At the upper limit of movement of the cylinder, the cylinder grippers are opened by the action of cam 66 (see Figures 8 and 11), whereupon the printed sheet is seized by the delivery grippers 71 (see Figure 3) preparatory to being moved to the jogger. During the upward movement of the cylinder and transfer table, a sheet of stock is fed from the stock pile toward the 20 transfer table, and when the cylinder and transfer table reach their upper limit of movement the sheet of stock is placed or deposited upon the transfer table, where it is held by suction extended through the apertures 121, which suction continues until the cylinder and the transfer table, moving downwardly therewith, have almost reached their lower limit of movement, whereupon the sheet is brought into proper registering 25 relationship with the cylinder and side guide. Under normal operating conditions the cylinder grippers grip the sheet of material, and the cylinder, which in the meantime at its lower limit of movement has become locked through the action of block 93, dog 90, and associated parts (see Figure 23), then rotates as it is moved upwardly during the printing operation. If, however, the sheet of material is not withdrawn 30 from the transfer table, the plunger 122 which has been forced outwardly will remain out in the path of movement of a switch arm 127 (Figure 7), so that upon the upward movement of the cylinder and transfer table the switch arm 127 will be moved upwardly, causing the motor circuit to be broken and the parts to be brought to a state of rest. 35 In connection with the pneumatic control mechanism, attention is directed to Figures 14, 15, 16 and 17. Mounted upon the cam shaft 30 is a cam 128 which controls the operation of valve 108, said valve having an operating rod 129 pivotally connected 40 at its lower end to one end of a lever 130, the opposite end of which is provided with a roller 131 riding on cam 128. The cam rotates in a counterclockwise direction as viewed in Figure 15, and in the position shown, the vacuum at the transfer table has 45 been cut off to permit the sheet to be registered, the vacuum being cut off during the interval on the cam indicated between reference letters $x-y$. The period on the cam 128 between y and z indicates the time during which the vacuum at the transfer table is on so that the plunger 122 may cause the opening of the motor switch through switch handle 127 during the upward movement of the cylinder if the sheet of material remains 50 on the transfer table instead of being taken by the cylinder. The period on the cam indicated by $z-w$ represents a period during which vacuum is cut off, the cylinder being about to start its downward movement when the point w on the cam is reached. The period on the cam indicated by $w-x$ is a period during which the suction is on at the transfer table, and accordingly on at 55 plungers 122 and 124 when a sheet of material is on the table to cover holes 121; the cylinder and transfer table during this time moving downwardly, and, as stated above, at the point x on cam 128 suction is cut off to permit registry of the sheet of material. It will be understood that every time the vacuum is cut on at the transfer table, with a sheet of material on the transfer table, the plunger 124 is moved outwardly, causing, through its stem 123, the lower end 60 of the dog 90 to be moved outwardly into the path of movement of the block 93 (see Figure 23). 65

Suction feed mechanism.

100

As mentioned hereinabove, the material to be printed is placed first upon the stock table 19 from which it is transferred sheet by sheet to the transfer table 120, from which the material is fed sheet by sheet to the cylinder to be printed, and from which it is taken by the delivery grippers and placed onto the jogger. It will be noted, therefore, that sheets of paper are conveyed in succession from the stock supply on one side of the cylinder to the latter and that the printed sheets of paper are conveyed in succession from said cylinder to the opposite side of the latter. The material is carried from the stock-pile to the transfer table by suction feed mechanism, including a suction shoe 173 (see Figure 18 adjacent Figure 1) loosely mounted in a frame 174, the suction shoe being connected by a flexible tube 175 to a pipe 176 connected to the source of suction through connections including a passageway 177 (see Figure 24) in one of the suction shoe carrying arms or feed levers 178 communicating with an opening 179 in the feed arm rock shaft 180 having openings 181 registering with a port in valve 182, which port communicates with a passageway 183 (see Figure 14) within the valve casing 106, said passageway 183 being controlled by the reciprocating valve 110 115 120 125 130 135 140 145 150 155 160 165 170 175 180 185 190 195 200

109. This valve is controlled by a cam 184 (sec Figures 16 and 17) mounted upon shaft 30 alongside cam 128. Operatively connecting the valve 109 and the cam 184 is a bar 185, the lower end of which is connected to a lever 186 pivoted intermediate its ends and having at its outer end a roller 187 which directly engages the cam 184. The suction is extended to the sucker shoe 173 at the time that it is desired to transfer a sheet of material from the stock table to the transfer table and during that period only, the cam 184 controlling the proper cut-off. At the time that the suction shoe 173 grips a sheet of material on the stock table 19 the cylinder and transfer table are in their lowermost positions, and it is during the upward movement of the cylinder and transfer table that the sucker shoe 173 is moved toward the transfer table, and at the upper limit of movement of the transfer table the sheet of material carried by the suction shoe 173 is deposited upon the transfer table whereupon suction is cut off from the suction shoe 173, releasing the sheet of material therefrom. At the same time suction is established at the transfer table for seizing and holding the sheet of material thereon. As mentioned above, the sucker shoe is carried by arms 178 mounted upon shaft 180 (see Figure 2), one of said arms 178 having a projection 188 at the free end of which is connected a rod 189 to the lower end of which is connected a roller 190 in engagement with a cam race 191 of a cam 192 mounted upon cam shaft 30. The lower end of the rod 189 is steadied and guided by a link 193 pivoted at one end to the rod and at the other end to the side frame. From this connection it will be appreciated that as the cam 192 is rotated the arms 178 and the sucker shoe carried thereby will be reciprocated back and forth between the stock-table and the transfer table. Pivots connected to the front end of the sucker shoe structure at 194 (see Figures 1 and 2) is a link 195, to the lower end of which is operatively connected a yieldably mounted block 196 movable back and forth in a slide member 197 pivoted at 198 to the arm 17. Pivots connected to the slide member 197 intermediate its ends is a spring-pressed rod 199 which has connected at its lower end one end of a lever 200 pivoted intermediate its ends at 201 to the side frame 11, the other end of the lever carrying a roller 202 which cooperates with a cam 203 whereby the sucker shoe is caused to dip into engagement with the top sheet of material on the stockpile at the proper time, as shown in Figure 1 of the drawings. The suction shoe mechanism is pivotally carried by the arms 178 from which such mechanism may be liberated by merely pressing a lever 230 (Figure 5) which is operatively associated

with a centering plug 231 slidably mounted in one of the arms 178. When the plug 231 is withdrawn from its normal position, the suction shoe mechanism, as a unit, may be withdrawn from the arms 178 first by 70 a sidewise and then by a lateral movement.

Registry mechanism.

The transfer table in addition to having an up and down movement with the cylinder 75 is given a rocking movement toward the cylinder as the transfer table and the cylinder are moving downwardly for front registering, and accordingly the transfer table is rocked away from the cylinder a small 80 amount as the cylinder and transfer table are moved upwardly. Also the transfer table is moved transversely for side registry, this movement taking place just as the table and cylinder reach their lower limit of 85 movement. Consideration will be given first to the forward and backward rocking movement of the transfer table for front registry.

Mounted upon each end of the rod 62 90 (see Figures 7 and 8) is an arm 135 to each of which is pivotally connected a turnbuckle 136 to the latter of which is pivotally connected an arm 137 pivoted intermediate its ends to pins 138 on the cylinder bearings. 95 Connected to the upper ends of the arms 137 is the frame carrying the transfer table. Pivotally secured to one of the turnbuckles (see Figure 19) is a block 139 slidably mounted in a slightly inclined stationary 100 cam or guide member 140 secured to the arm 17. Accordingly, when the cylinder is moved upwardly toward its upward limit of movement the transfer table is rocked away from the cylinder, and when the cylinder 105 and transfer table are moved downwardly the latter is caused to rock toward the cylinder so that the advancing edge of the sheet of material approaches closer and closer to the cylinder grippers, and at the point 110 where the cylinder and transfer table reach their lower limit of movement the transfer table has rocked toward the cylinder grippers to the extent that the sheet of material is placed directly in engagement with the 115 cylinder gripper pins under the heads thereof. As the transfer table approaches this lower limit of movement, the transfer table also is moved to one side for side registry purposes by means of the following mechanism: One of the transfer table supporting arms 137 (see Figure 6) slidably receives a pin 141 projecting from the transfer table 120 to accommodate side movement of the latter for side registering. The other transfer table supporting arm 137 is clamped to the transfer table structure and has two ears 142 (see Figures 19, 20, and 22) between which is received a tongue 143 formed at 125 one end of a pin 144 carrying a roller 145 130

movably mounted in an arcuate slot 146 formed in a slide 147 which is slidably mounted in a guiding member 148 secured to the cylinder bearing. The pin 144 is 5 mounted at one end of an arm 149 pivoted at 150 whereby the arm may rock transversely in the guiding member 148, the guiding member 148 having an oblong opening 151 (see Figure 22) to permit rocking movement of the arm 149 with the parts carried thereby. The lower end of the slide 147 is slotted to receive the headed portion 152 (see Figures 19 and 20) of a spring-pressed reciprocating rod 153 which is moved upwardly by the lower end of said rod passing into engagement with a projection 154 (see Figure 2) carried on the side arm 17. In this connection, it will be understood that the rod 153 and the associated 20 parts are carried on the cylinder bearing so that it is during the last part of the downward movement of the cylinder that the rod 153 is moved upwardly, and during this upward movement of the rod 153 the slide 147 connected thereto is moved upwardly, causing the pin 144, through effect of cam slot 146, to move to the left as viewed in Figure 20, the transfer table accordingly, as a result of the connections 142 and 143, being shifted laterally for side registering.

It will be understood that at the time that the transfer table is moving sidewise the suction at the table is cut off, one edge of the sheet of material passing into engagement 35 with a side guide 126 (see Figures 6 and 7) for limiting sidewise movement of the sheet of material for side registering purposes, as the transfer table continues its lateral movement. This side guide arm 126 dips down 40 into the path of movement of the sidewise moving paper just at the time of registering. The arm 126, which normally is held elevated in any suitable manner, is clamped in a jaw member 155 which in turn is secured 45 to a rod 156, the jaw member at the rear end having a projection 157 which passes into engagement with a stationary cam 158 on the gib plate to give the necessary dipping movement to the arm 126 at the proper moment, the outer end of the arm passing into 50 one of a plurality of grooves 159 (see Figure 26).

Pivottally connected at 160 (see Figures 7 and 8) to the upper end of one of the arms 55 137 is a rocker plate 161, the lower portion of which is connected to a fixed rod 162 in turn secured to a casting 163 forming the support for the side registry bar 126. The free end of this rocker plate 161 underlies and 60 supports a finger 164 which is secured to the ironing bar 165 which is pivottally connected at 166 to a pair of ears on the frame of the transfer table. From this arrangement it is apparent that when the upper ends of the 65 arms 137 are swung toward the cylinder dur-

ing the downward movement of the latter, the ironing bar 165 will be permitted to drop into its lowermost position, which position it assumes when the cylinder is in its lowermost position and at which time the sheet of 70 material is drawn from the transfer table onto the cylinder by the cylinder grippers, the ironing bar 165 ironing out the sheet of material. When the upper ends of the arms 75 137 are swung away from the cylinder during an upward movement of the latter the ironing bar 165 is raised, it finally taking the position shown in Figure 7 where the cylinder is in its uppermost position.

Delivery mechanism.

The printed sheets of material are taken from the cylinder when the latter is in its upper limit of movement and delivered onto the jogger by the delivery grippers 71 (see 85 Figures 1, 2, 3, and 4) which include upper and lower jaws 204 and 205 (see Figure 4), which normally are held in closed position by a plurality of springs 206 surrounding pins 207 secured to a bar 208 interposed between the upper and lower jaws. These jaws at their rear ends are secured to a shaft 209 having flattened portions to which also are connected delivery levers 210 which are secured to a rock shaft 211 (see Figure 3). 90 Also secured to the rock shaft is a leg 212 (see Figure 4) having a guide groove for the reception of a roller 213 mounted upon one side of a cam 214 which is mounted upon the main shaft 27. Accordingly, as the cam 100 214 is rotated the delivery levers are oscillated back and forth between the cylinder 45 and the jogger 21. The jaws of the delivery grippers must be open at the time that a printed sheet of material is to be withdrawn 105 from the cylinder and also at the time when the printed sheet is to be delivered to the jogger. To open the jaws, I have provided a lever 215 which is operatively connected to the bar 208 and also connected to a collar 216 110 slidably mounted upon one of the delivery levers 210 to which collar is pivotally connected a link 217, which in turn is pivotally connected to one arm of a bell crank lever 218 pivotally connected to the frame at 219. 115 The other arm of the bell crank lever is provided with a roller 220 which cooperates with a cam 214 having projections 221 and 222. When the cam projection 222 engages the roller, the gripper jaws 204 and 205 are 120 open for gripping the printed sheet on the cylinder to remove the sheet therefrom, and when the roller 220 is engaged by projection 221 the printed sheet has been conveyed to and is located over the jogger, at which time 125 the jaws are again open to permit said sheet to be deposited on the jogger. At the time that the delivery grippers grip the printed sheet of material on the cylinder it is necessary that the active ends of the grippers be 130

dipped into engagement with the printed sheet. To cause the grippers to dip I have provided a lever 223 which is operatively connected with the jaws 204 and 205 and which has at its lower end a roller 224 which is movable in an arcuate-shape cam 225 pivoted intermediate its ends at 226 to the side frame 11. Operatively connected to the arcuate shape cam 225 is a link 226^a having at its lower end a roller 227 which cooperates with a cam 228 for transmitting to the arcuate shape cam 225 a rocking motion which transmits to the shaft 209, and accordingly the gripper jaws 204 and 205, a dipping action. It will be understood that just as soon as the jaws grip the printed sheet, the jaws are rocked slightly upwardly for completely releasing the printed sheet from the cylinder grippers and at that time the delivery grippers are started on their movement toward the jogger. A spring 229 holds the roller 227 in engagement with the cam 228 so that the movements transmitted to the arcuate shape cam 225 at all times correspond to the cam profile.

The main shaft 27 is provided with a crank arm 230 (see Figure 3) to which is pivotally connected a link 231, the upper end of which link is pivotally connected to the bed plate 232 which receives and carries the usual chase frame. In this connection, it will be noted that when the bed plate is in its lowest position the cylinder is in its highest position, and that said parts rise and fall rectilinearly in vertical planes, and in an opposite sense to give a high speed balanced action. Also, it will be noted that the bed plate has secured thereto a rack bar 80 (Figures 1 and 9) which at all times is in mesh with the cylinder drive gear 79 whereby half the vertical throw is made by the bed plate and the parts secured thereby, and the other half made by the cylinder.

In a general résumé of the operation of the press, it will be understood that when the cylinder and transfer table are at their upper limit of movement, the cylinder is unlocked; that a sheet of material has been fed from the stock table to the transfer table; that the suction at the gripper shoe has been cut off; that the suction at the transfer table has been cut in, and accordingly with the sheet of material on the transfer table the plunger controlling the motor switch has been moved outwardly to open the switch upon upward movement of the cylinder and transfer table if the sheet still remains on the latter during its upward movement; that the plunger controlling the cylinder lock dog has been moved outwardly that the cylinder may be locked at its lower limit of movement; that the cylinder grippers are opened; and that the delivery grippers grip the sheet of

printed material preparatory to conveying same from the cylinder to the jogger. Also, it will be understood that when the cylinder and transfer table are at their lower limit of movement the cylinder is locked; that the sheet of material on the transfer table has been brought into side and front registry with the cylinder; that the cylinder grippers are open to grip the sheet of material to withdraw the latter from the transfer table preparatory to the upward printing movement of the cylinder; that the suction feeder shoe is dipped into engagement with the top sheet on the stock table; that suction is cut in at the suction shoe; and that the delivery grippers are over the jogger and have deposited the printed sheet thereon.

During the upward movement of the cylinder and transfer table, the suction feed gripper is conveying a sheet of material from the stock table to the transfer table, and the delivery grippers are moving toward the cylinder. Also for a limited period suction is cut in on the transfer table to maintain motor switch control plunger in its outward trip position to open the motor switch if the sheet of material still remains on the transfer table during upward movement of the latter. The cylinder in its upward printing movement is locked and rotates, while in its downward movement it is unlocked and does not rotate.

It is my intention to cover all modifications falling within the spirit and scope of the following claims.

I claim:

1. In a printing press, a movable type bed, a cooperating cylinder mounted for rotation and also for reciprocating motion, and means pneumatically controlled by a fed sheet of material whereby said cylinder rotates during a movement in one direction and does not rotate during a movement in another direction.

2. In a printing press, a cylinder mounted for rotation and also for rectilinear movement, a type bed rectilinearly movable in an opposite direction with respect to said cylinder, and means pneumatically controlled by sheet feeding conditions whereby said cylinder rotates during a movement in one direction and does not rotate during movement in another direction.

3. In a printing press, a type bed, a co-operating cylinder mounted for rotation and also for reciprocating motion, and means pneumatically controlled by sheet feeding conditions whereby said cylinder rotates during a movement in one direction and does not rotate during a movement in an opposite direction.

4. In a printing press, a cylinder mounted for rotation and also for a vertical reciprocating motion, a type bed movable in

- an opposite direction with respect to said cylinder, and means pneumatically controlled by sheet feeding conditions whereby said cylinder rotates during a movement in 5 one direction and does not rotate during a movement in another direction.
5. In a printing press, a type bed, a co-operating cylinder mounted for rotation and also for a vertical reciprocatory motion, and means pneumatically controlled by sheet feeding conditions whereby said cylinder rotates during an upward movement and does not rotate during a downward movement.
- 10 6. In a printing press, a type bed, a co-operating cylinder mounted for rotation and also for reciprocatory motion, and a lock for said cylinder pneumatically controlled by a sheet feeding condition whereby the cylinder rotates during a movement in one direction and does not rotate during a movement in another direction.
- 15 7. In a printing press, a cylinder mounted for rotation and also for reciprocatory motion, a lock member which in one position locks said cylinder for rotation during a movement of the latter in one direction and which in another position unlocks said cylinder so that the latter does not rotate, and means whereby said lock member is pneumatically controlled by a fed sheet of material.
- 20 8. In a printing press, a cylinder mounted for rotation and also for reciprocatory motion, a type bed cooperating therewith, a lock member, and means pneumatically controlled by a sheet feeding condition for moving said lock member whereby the cylinder will be caused to rotate during movement in one direction and will not rotate during a movement in another direction.
- 25 9. In a printing press, a cylinder mounted for rotation and also for reciprocatory motion, a type bed associated therewith, and means carried by the cylinder and pneumatically controlled by a sheet feeding condition whereby said cylinder rotates during a movement in one direction and does not rotate during a movement in another direction.
- 30 10. In a printing press, a cylinder mounted for rotation and also for reciprocatory motion, and a lock carried by the cylinder and in part pneumatically controlled by a sheet of material whereby said cylinder rotates during a movement in one direction and does not rotate during a movement in another direction.
- 35 11. In a printing press, a cylinder mounted for rotation and also for reciprocatory motion, an actuating member for said cylinder whereby the latter may be rotated, and means pneumatically controlled by a sheet of material for locking said cylinder with respect to said actuating member.
- 40 12. In a printing press, a cylinder mounted for rotation, an actuating member for said cylinder whereby the latter may be rotated, and means pneumatically controlled by a fed sheet of material for locking said cylinder with respect to said actuating member.
- 45 13. In a printing press, a cylinder mounted for rotation and also for reciprocatory motion, a co-operating type bed, an actuating member for said cylinder whereby the latter may be rotated, and means for unlocking said cylinder with respect to said actuating member regardless of sheet feeding conditions.
- 50 14. In a printing press, a cylinder mounted for rotation and also for reciprocatory motion, an actuating member for said cylinder whereby the latter may be rotated, and means for locking and unlocking said cylinder with respect to said actuating member, one of said conditions of said cylinder being pneumatically controlled.
- 55 15. In a printing press, a cylinder mounted for rotation and also for reciprocatory motion, a gear which may have a locked and unlocked relationship with said cylinder whereby the latter may rotate or not during its other movements, means whereby said gear may be actuated, and means whereby the locked relationship may be pneumatically controlled.
- 60 16. In a printing press, a cylinder mounted for rotation and also for reciprocatory motion, a rack member, a gear carried by said cylinder and being in mesh with said rack, and means whereby said cylinder may be locked to or unlocked from said gear member for causing the cylinder to rotate or not during other movements of said cylinder, the locked relationship being pneumatically controlled.
- 65 17. In a printing press, a type bed, a co-operating cylinder mounted for rotation and also for reciprocatory motion, and means pneumatically controlled by a fed sheet whereby said cylinder may be locked for rotation during one part only of its cycle of movement.
- 70 18. In a printing press, a cylinder mounted for rotation and also for reciprocatory motion, and means whereby said cylinder may be locked for rotation during one part of its cycle of movement and unlocked during another cycle of its movement, one of said conditions of the cylinder being pneumatically controlled.
- 75 19. In a printing press, a cylinder mounted for rotation, and means whereby said cylinder may be locked for rotation at one limit of movement as a result of pneumatic action on a fed sheet of material and unlocked at another limit of movement.
- 80 20. In a printing press, a mounted type bed, a co-operating cylinder mounted for rotation and also for vertical movement, and

- means pneumatically controlled by sheet feeding conditions whereby said cylinder may be locked in its lower limit of movement so that it will rotate during an upward movement and be unlocked at its upper limit of movement so that it will not rotate during a downward movement.
21. In a printing press, a cylinder and a type bed mounted for reciprocatory movement in opposite directions, and means whereby said cylinder may be locked for rotation during the printing movement and unlocked to prevent rotation during the idling movement, the relative movement being pneumatically controlled in accordance with sheet feeding conditions.
22. In a printing press, a type bed, a co-operating cylinder mounted for rotation and also for vertical movement, means pneumatically controlled by sheet feeding conditions whereby said cylinder may be locked in its lower limit of movement so that it will rotate during an upward movement and be unlocked at its upper limit of movement so that it will not rotate during a downward movement, and means for yieldably holding said cylinder in unlocked position.
23. In a printing press, a cylinder mounted for rotation and also for reciprocatory motion, a lock whereby said cylinder may be rotated during a movement in one direction and does not rotate during movement in another direction, the rotation being controlled as the result of pneumatic action on a fed sheet of material.
24. In a printing press, a cylinder mounted for rotation and also for reciprocatory motion, a lock member whereby the cylinder may rotate or not according to the position of said lock, a member through which motion is transmitted to said lock member, and suction controlled means for changing the operative position of said last-mentioned member.
25. In a printing press, a cylinder mounted for rotation and also for reciprocatory motion, a lock member for said cylinder whereby the cylinder may rotate or not as the latter is reciprocated, and fluid-controlled means for controlling a movement of said lock member.
26. In a printing press, a cylinder mounted for rotation and also for reciprocatory motion, a lock member for said cylinder whereby the cylinder may rotate or not as the latter is reciprocated, and fluid-controlled means for controlling a locking movement of said lock member.
27. In a printing press, a cylinder mounted for rotation and also for reciprocatory motion, a lock member for said cylinder, a dog through which motion is transmitted to said lock member, lock actuated means for engaging said dog under certain conditions, and pneumatically controlled means for controlling the position of said dog to determine whether or not the lock member shall be moved into a given position.
28. In a printing press, a cylinder, a transfer table associated therewith, locking means for said cylinder, and means whereby said cylinder will not become locked if material is not placed on said transfer table at a given time during the cycle.
29. In a printing press, a cylinder mounted for rotation and also for reciprocatory movement, a transfer table associated with said cylinder, locking means for said cylinder, and means whereby said cylinder will not become locked if material is not fed to said transfer table during the operation of the press.
30. In a printing press, a cylinder mounted for rotation and also for vertical reciprocatory movement, a transfer table associated with said cylinder and movable therewith, locking means for said cylinder, and means whereby said cylinder will not become locked if material is not placed on said transfer table at the upper limit of its movement.
31. In a printing press, a cylinder, a lock member for said cylinder whereby the latter may be rotated or not, a transfer table, and suction controlled means associated with said transfer table whereby said lock member is controlled.
32. In a printing press, a cylinder, a lock member for said cylinder whereby the latter may be rotated or not, a transfer table, and means whereby movement of said lock member will be controlled depending upon whether or not a sheet of material is placed on said transfer table during the operation of the press.
33. In a printing press, a cylinder, a lock member for said cylinder whereby the latter may be rotated or not, a transfer table, and means whereby said lock member may be given a locking movement depending upon whether or not a sheet of material is placed on said transfer table during the operation of the press.
34. In a printing press, a bodily movable printing cylinder, a frame therefor, and a sheet handling transfer table carried entirely thereby and rockable thereon to facilitate the feeding of sheet material to said cylinder.
35. In a printing press, a bodily movable printing cylinder, a frame therefor, a sheet handling transfer table carried entirely thereby, and means whereby said transfer table may have a rockable motion with respect to said printing cylinder for registering purposes.
36. In a printing press, a bodily movable printing cylinder, a frame therefor, a sheet handling transfer table carried entirely

- thereby, and means whereby said transfer table may be given a dipping motion with respect to said cylinder for registering purposes.
37. In a printing press, a printing cylinder mounted for vertical movement and having a frame, a transfer table secured to the cylinder frame, and means whereby said transfer table is given a dipping motion toward the cylinder during a downward movement of the latter for registering purposes.
38. In a printing press, a printing cylinder mounted for vertical movement and having a frame, a transfer table secured to the cylinder frame, and means whereby said transfer table is given a dipping motion toward the cylinder during a downward movement of the latter for registering purposes and whereby said transfer table is rocked away from the cylinder during an upward movement of the latter.
39. In a printing press, a printing cylinder mounted for vertical movement, a transfer table carried therewith, and cam means for actuating said transfer table relative to said cylinder for registering purposes.
40. In a printing press, a bodily movable printing cylinder, a transfer table associated therewith to facilitate the feeding of sheet material, and means movable therewith for giving said transfer table a sheet registering movement.
41. In a printing press, a bodily movable printing cylinder, a sheet handling transfer table associated therewith, and means movable therewith for giving said transfer table a lateral sheet registering movement.
42. In a printing press, a bodily movable printing cylinder, a sheet handling transfer table associated therewith, and means movable therewith for giving said transfer table a lateral sheet registering movement, said means including a slidably mounted cam member operatively connected to said transfer table.
43. In a printing press, a bodily movable printing cylinder, a sheet handling transfer table associated therewith, and cam means movable therewith for giving said transfer table a lateral sheet registering movement.
44. In a printing press, a bodily movable printing cylinder, a sheet handling transfer table associated therewith, a movable cam member movable with the cylinder and table, and means for actuating said cam member for giving the transfer table a lateral sheet registering movement during a given movement of said cylinder.
45. In a printing press, a printing cylinder movable upwardly and downwardly, a sheet handling transfer table associated therewith, a movable cam member movable with the cylinder and table, and means for actuating said cam member for giving the transfer table a lateral sheet registering movement near
- the lower limit of movement of said cylinder.
46. In a printing press, a movably mounted printing cylinder, a sheet handling transfer table associated therewith, a movably mounted cam slide member movable with the cylinder, means whereby said slide member may be moved in one direction for giving said transfer table a lateral sheet registering movement, and means whereby said cam member may be moved in an opposite direction for moving said transfer table to its normal position.
47. In a printing press, a movably mounted cylinder frame, a printing cylinder carried thereby, a sheet handling transfer table movable with said cylinder and laterally movable with respect to the cylinder, and cam means carried by the cylinder frame for giving said transfer table a sheet lateral registering movement during movement of said cylinder frame.
48. In a printing press, a cylinder, a movable frame therefor, a sheet handling transfer table carried entirely thereby, and means for giving said transfer table a dipping motion with respect to said cylinder for front registering purposes and for giving said transfer table a lateral movement for side registering purposes.
49. In a printing press, a cylinder, movable upwardly and downwardly, a sheet handling transfer table carried entirely thereby, and means for giving said transfer table a dipping motion with respect to said cylinder for front registering purposes and for giving said transfer table a lateral movement for side registering purposes during a downward movement of said cylinder.
50. In a printing press, a printing cylinder, means for driving the moving parts of the printing press, a transfer table associated with the cylinder, and means whereby the press is stopped when a sheet of material remains on the transfer table after it should have passed to the cylinder.
51. In a printing press, a printing cylinder, means for driving the moving parts of the printing press, a transfer table associated with the cylinder, and means whereby the press is stopped when a sheet of material remains on the transfer table after a predetermined length of time during the operation of the press.
52. In a printing press, a printing cylinder, a motor for driving the moving parts of the printing press, a transfer table, and means whereby said motor is stopped when a sheet of material remains on the transfer table after a given point during the cycle of the machine is reached.
53. In a printing press, a printing cylinder, an electric motor for driving the moving parts of the cylinder having a switch, a transfer table associated with the printing

cylinder, and means whereby the motor switch is opened when a sheet of material remains on the transfer table after it should have passed to the cylinder.

- 5 54. In a printing press, a printing cylinder, means for driving the moving parts of the printing press, a transfer table associated with said cylinder, and means carried by the frame of the printing cylinder
10 for causing the printing press to come to a state of rest when a sheet of material remains on the transfer table after it should have passed to the cylinder.

55. In a printing press, a movably mounted type bed, a cooperating printing cylinder capable of being locked for rotation during a printing movement and unlocked otherwise, means whereby the locking condition is pneumatically controlled, means normally
20 holding said cylinder against rotation when unlocked, and means for releasing the cylinder from said holding means.

56. In a printing press, a printing cylinder capable of being locked for rotation during a printing movement and unlocked otherwise, means whereby the locked condition is pneumatically controlled by fed sheet material, and means normally releasably holding said cylinder against rotation when unlocked, said cylinder being released from said holding means for making ready.

57. In a printing press, a printing cylinder capable of being locked for rotation during a printing movement and unlocked otherwise, means whereby the locking of said cylinder is pneumatically controlled by fed sheet material, means normally holding said cylinder against rotation when unlocked, and means carried by the cylinder whereby the latter may be released from said holding means.

Signed at Milwaukee, Wisconsin, this 7th day of October, 1919.

EDWARD CHESHIRE.

cylinder, and means whereby the motor switch is opened when a sheet of material remains on the transfer table after it should have passed to the cylinder.

54. In a printing press, a printing cylinder, means for driving the moving parts of the printing press, a transfer table associated with said cylinder, and means carried by the frame of the printing cylinder

10 for causing the printing press to come to a state of rest when a sheet of material remains on the transfer table after it should have passed to the cylinder.

55. In a printing press, a movably mounted type bed, a cooperating printing cylinder capable of being locked for rotation during a printing movement and unlocked otherwise, means whereby the locking condition is pneumatically controlled, means normally

20 holding said cylinder against rotation when unlocked, and means for releasing the cylinder from said holding means.

56. In a printing press, a printing cylinder capable of being locked for rotation during a printing movement and unlocked 25 otherwise, means whereby the locked condition is pneumatically controlled by fed sheet material, and means normally releasably holding said cylinder against rotation when unlocked, said cylinder being released from 30 said holding means for making ready.

57. In a printing press, a printing cylinder capable of being locked for rotation during a printing movement and unlocked otherwise, means whereby the locking of 35 said cylinder is pneumatically controlled by fed sheet material, means normally holding said cylinder against rotation when unlocked, and means carried by the cylinder whereby the latter may be released from said 40 holding means.

Signed at Milwaukee, Wisconsin, this 7th day of October, 1919.

EDWARD CHESHIRE.

Certificate of Correction.

It is hereby certified that in Letters Patent No. 1,567,178, granted December 29, 1925, upon the application of Edward Cheshire, of Milwaukee, Wisconsin, for an improvement in "Printing Presses," an error appears in the printed specification requiring correction as follows: Page 11, line 85, claim 47, strike out the word "sheet" and insert the same after the word "lateral" in the same line; and that the said Letters Patent should be read with this correction therein that the same may conform to the record of the case in the Patent Office.

Signed and sealed this 26th day of January, A. D. 1926.

[SEAL.]

WM. A. KINNAN,
Acting Commissioner of Patents.
